UNITED STATES PATENT OFFICE.

LOUIS NAGY, OF HAMILTON, ONTARIO, CANADA, ASSIGNOR OF THREE-TENTHS TO
MICHAEL DARADICE.

AEROPLANE.

Application filed September 3, 1927. Serial No. 217,346.

This invention relates to an aeroplane of new and novel construction, embodying certain features hereinafter more fully described, claimed and illustrated in the accompanying drawing.

The object of the invention is to provide an aeroplane embodying a plurality of propelling members so positioned as to propel and elevate the aeroplane.

10 Fig. 1 is a top plan view of my improved aeroplane.

Fig. 2 is a side elevational view thereof.

Fig. 3 is a front elevational view thereof.

15 Fig. 4 is an enlarged fragmentary sectional view taken on the line 4—4 of Fig. 2.

Fig. 5 is a fragmentary sectional view illustrating particularly the means of pivoting the wings of my improved device.

20 Fig. 6 is a similar fragmentary sectional view thereof.

Fig. 7 is an enlarged fragmentary view illustrating a modification of my improved aeroplane.

25 Fig. 8 is a transverse sectional view taken on the line 8—8 of Fig. 7.

As here embodied my improved aeroplane comprises a body 10 of hollow construction, preferably of cylindrical shape and pointed at either extremity. The body 10 is of 30 frame construction, covered with any desired suitable material, so as to provide suitable accommodations for the operators and passengers.

35 A motor 11, such as usually employed to propel aeroplanes is mounted in the fore part or forward extremity of the body 10, and has attached thereto, the usual propeller 12, as a means of propelling my improved aeroplane.

40 A pair of wings, comprising the usual upper and lower members 13 and 14, supported by the struts 15, are extended horizontally from the sides of the body 10. The said wings are secured to the rod 16, pivotally mounted, as at 17, in the sides of the body 10. A pair of sectors 18, are secured 45 to the rod 16, and mesh with the worms 19, secured to the shafts 20, rotatively mounted as at 21, and 22 in extended elements of the body 10. The bevel gears 23 are attached to the shafts 20 and mesh with the bevel gears 24 attached to the shafts 25, rotatively

mounted in the body 10. The crank members 26 are attached to the shafts 25, and are provided with handle elements 27.

55 The above described construction is such as will permit the said wings to be pivoted in any desired angular position so as to permit my improved aeroplane to ascend and descend as may be desired.

A stud 28 is adapted to engage in an aperture formed in the wings, and in an arc opening formed in the body 10, as a means of holding the said wings in any desired angular position, by tightening the nut 29, 65 threadedly attached to the stud 28, so as to force the lock nut 30 in position thereon.

60 A second motor 31 is mounted in the body 10, and is provided with a bevel gear 32, secured to the crank shaft of the said motor. 70 The bevel gear 32, meshes with the bevel gear 33, secured to the shaft 34, rotatively mounted in the body 10. The propeller 34 is secured to the extended extremity of the shaft 34, and is positioned horizontally. The 75 above described construction is such as will permit the propeller 35, coacting with the propellers hereinafter described, to elevate or raise the said aeroplane.

70 The bevel gear 36, meshes with the above 80 mentioned bevel gear 32, and is attached to the shaft 37, rotatively mounted in the body 10, and in the bracket 38, secured to and extended from the upper portion of the body.

85 Sprocket wheels 39 are attached to the shafts 40 and 41, rotatively mounted in the upper portion of the body 10, and the bracket 38. The chain 42 is extended over the sprocket wheels 39, and engages a similar sprocket wheel 43 attached to the shaft 37. 90 The propellers 44 are provided with threaded central apertures, adapted to engage the threaded upper portions of the said shafts 37, 40, and 41, which are provided with enlarged extremities, as a means of holding 95 the propellers 43 in place on the said shafts.

The above described construction is such as will permit the propellers 44 to, at first, assume the position designated by the reference numeral 45, at the upper extremities of the said shafts, when the motor 31 is started so as to permit the above mentioned propeller 34, to do the initial lifting. It should be understood that the propellers 44 having

assumed the latter mentioned position, will at that time assist the propeller 34 in lifting the said aeroplane. I have also provided locking members 46 which may be engaged over the threaded portions of the said shafts, so as to hold the propellers 44, in a fixed position on the said shafts.

I have also provided the usual rudder 47, hinged as at 48, to the tail member 49, and provided with a tiller 50. Flexible members 51 and 52 are connected to the extremities of the tiller 50, and to the bell cranks 53, pivotally attached as at 54, to the body 10, of the aeroplane. The bell cranks 53 are provided with handle elements 55, as a means of pivoting the rudder 47, so as to steer my improved aeroplane to the right or to the left.

I have also provided the usual landing wheels 56, secured to the shafts 57, rotatively mounted in the brackets 58, extended from and secured to the body 10, such as are ordinarily provided to assist in landing.

It will be understood that the body 10, has hinged thereto, a door 59, permitting access to the interior of the body 10, which is provided with a compartment 60, equipped with a suitable seat 61, and control board 62, to accommodate the usual control mechanism for manipulating the motors of my improved aeroplane. It should be further understood that I do not necessarily limit my improved aeroplane to the particular construction, as above set forth as regards the body accoutrements, but to all types and classes of bodies, such as used for passenger or freight service, or in modern warfare.

In Figs. 7 and 8 of the accompanying drawing, I have shown the sprocket wheels 39, rotatively mounted on the shafts 40 and 41. The disc members 65 are slidably mounted on the shafts 40 and 41, and are secured thereto, by keys 66. The pins 67 are secured to and extended from the disc members 65, and are adapted to engage in apertures 68, formed in the sprocket wheels 39. The expansion springs 69 normally hold the pins 67 in disengagement with the said apertures formed in the sprocket wheels. The levers 70 are pivotally attached intermediate to the lug elements 71 of the above mentioned bracket 38 and are provided with forked extremities 72, engaging the disc members 65. The rods 73 are pivotally attached, as at 74 and 75, to the lever 70, and to the lever 76, pivotally attached intermediate to the bracket 77, secured to any suitable, convenient part of my improved aero-

plane. The threaded blocks 78 are provided with extended elements 79 engaging in elongated openings formed in one extremity of the levers 76. The threaded blocks 78 are adapted to receive the screws 80, rotatively mounted in the brackets 81 and 82, secured to any suitable convenient part of my improved aeroplane. The crank 83 is secured to the screw 80, and is provided with a handle 84.

The above described construction is such as will permit the shafts 40 and 41 to be rotated by the sprocket wheels 39, when the pins 67 are engaged in the apertures 68, by means of rotating the cranks 83. This construction is provided as a means of permitting the propellers 44 mounted on the said shafts 40 and 41 to be operatively connected, as may be desired, so as to permit my improved aeroplane to be lifted gradually, increased lifting power thereby being secured.

Having thus described my invention, what I claim as new and desire to protect by Letters Patent of the United States is as follows:

1. In a device of the class described, a propeller operatively connected with a prime mover and arranged for lifting the device, shafts connected for rotation together with the said propeller, and having threaded portions, and propellers threadedly engaged on the said threaded portions and arranged for lifting the device.

2. In a device of the class described, a propeller operatively connected with a prime mover and arranged for lifting the device, shafts connected for rotation together with the said propeller, and having threaded portions and enlarged extremities, and propellers threadedly engaged on the said threaded portions and held against displacement off of the shafts by the said enlarged extremities and arranged for lifting the device.

3. In a device of the class described, a propeller operatively connected with a prime mover and arranged for lifting the device, shafts connected for rotation together with the said propeller, and having threaded portions, and propellers threadedly engaged on the said threaded portions and arranged for lifting the device, and locking members engaged on the shafts and arranged for holding the latter mentioned propellers in fixed positions on the shafts.

In testimony whereof I have affixed my signature.

LOUIS NAGY.
